(57) **CLAIM**

(22) **Filed:** **Apr. 24, 2019**

We claim the ornamental design for a refrigerator, as shown and described.

(30) **Foreign Application Priority Data**

DESCRIPTION

Feb. 22, 2019 (KR) 30-2019-0008107

FIG. 1 is a front perspective view of a refrigerator showing our new design;

(51) **LOC (12) Cl.** **15-07**

FIG. 2 is a front view thereof;

(52) **U.S. Cl.**

FIG. 3 is a rear view thereof;

USPC **D15/89**

FIG. 4 is a left-side view thereof;

(58) **Field of Classification Search**

FIG. 5 is a right-side view thereof;

USPC D15/79-91

FIG. 6 is a top view thereof;

CPC .. F25D 11/00; F25D 17/065; F25D 2325/022;

FIG. 7 is a bottom view thereof;

F25D 23/069; F25D 25/025; F25D 11/02;

FIG. 8 is an enlarged view of the encircled portion in FIG.

F25D 17/062; F25D 21/12; F25D 21/125;

1; and,

F25D 21/14; F25D 2317/061; F25D

FIG. 9 is an enlarged partial cross-sectional view thereof
2317/067; F25D 2323/021; F25D

2323/024; F25D 23/028; F25D 23/04;

taken vertically through line 9-9 in FIG. 2.

F25D 23/066; F25D 23/085; F25D

The dash-dash broken lines in the figures depict portions of

23/087; F25D 23/126; F25D 2400/02;

the claimed design. The dot-dash broken lines in the figures

F25D 2400/06; F25D 2400/361; F25D

represent boundaries of the claimed design and form no part thereof.

2400/40; F25D 25/005; F25D 25/02;

(Continued)

F25D 2600/02; F25D 2700/02; F25D

The dot-dot-dash broken lines encircling portions of the claimed design that are illustrated in enlargements form no part of the claimed design.

The jagged dot-dot-dash broken lines indicate a removal boundary and form no part of the claimed design.

1 Claim, 9 Drawing Sheets
